UNITED STATES PATENT OFFICE.

JAMES J. JENNINGS, OF CHICOPEE, MASSACHUSETTS, ASSIGNOR TO DRAPER CORPORATION, OF HOPEDALE, MASSACHUSETTS, A CORPORATION OF MAINE.

FILLING-REPLENISHING LOOM.

Application filed July 7, 1923. Serial No. 650,148.

To all whom it may concern:

Be it known that I, JAMES J. JENNINGS, a citizen of the United States, residing at Chicopee, in the county of Hampden and State of Massachusetts, have invented an Improvement in Filling-Replenishing Looms, of which the following description, in connection with the accompanying drawings, is a specification, like characters on the drawings representing like parts.

This invention relates to filling replenishing looms and more particularly to the means for controlling the filling end of the outgoing filling carrier or bobbin.

In so called "feeler looms" provided with mechanism for replenishing the filling prior to complete exhaustion of the thread in the running shuttle, it has heretofore been proposed to cut the filling adjacent the shuttle or sever its connection with the outgoing filling carrier or bobbin and to then move the filling end frontwardly into the range of action of a temple thread cutter adjacent the cloth selvage. In mechanism heretofore proposed the piece of filling between the cloth selvage and shuttle has been retained by a holder or catcher and finally released therefrom, so that the pieces of severed filling drop to the under portion of the loom and there accumulate upon the running parts of the loom beneath. In these constructions it has been customary for the loom attendant to reach down into the lower portion of the loom and remove the filling ends therefrom, an operation dangerous to the loom attendant and inconvenient of accomplishment.

One of the objects of the present invention is to provide mechanism whereby the filling between the cloth selvage and the shuttle of the outgoing filling carrier may be severed adjacent the shuttle and also adjacent the cloth selvage and then be held by a thread end holder of novel construction so that the loom attendant may at his pleasure remove the filling ends from the holder which is conveniently situated for this purpose. In accordance with the present invention, the thread end holder is located between the cloth selvage and shuttle and comprises jaws having friction material on their opposed faces which engage the filling end between the cloth selvage and shuttle, move it frontwardly after it has been cut adjacent the shuttle and subsequently hold and maintain

the filling end in their control after it has been severed by the temple thread cutter.

In carrying the invention into practical effect, the jaws of the thread end holder are moved rearwardly on call for replenishment of filling and are opened during their rearward movement by a jaw opener in order to receive the filling between the jaws which thereupon becomes engaged by the friction material carried by the jaws, and is moved frontwardly as the jaws themselves return to their initial position.

The friction material between the jaws comprises a series of wire teeth which may be conveniently provided by a piece of card clothing and which serve to hold the filling end, and it may be desirable in some cases to provide the face of the opposing jaw with friction material, such as felt or the like, the result being that when the filling end has been severed adjacent the shuttle and adjacent the cloth selvage, the jaws will effectively hold the filling end or accumulation of such ends and by retaining them in front position present them in convenient location for removal by the loom attendant.

The various features of the invention and new combination of parts will best be made clear from the following description and the accompanying drawings of one good form of the invention.

In the drawings:

Fig. 1 is a front perspective view of one side of a loom provided with the present invention, some of the parts being omitted for clearness of illustration;

Fig. 2 is an enlarged perspective view, showing the filling or thread end holder in front position and holding a severed filling end or thread; and

Fig. 3 is a side elevation showing the jaws of the thread end holder in open position ready to receive the end of filling.

The loom frame 1 has mounted thereon the usual transverse or rock shaft 2 which is supported in bearings 3 secured at opposite sides of the loom and by rocking movement of which through the usual feeler mechanism filling replenishment is effected. It has not been deemed necessary herein to show the feeler mechanism at the opposite side of the loom nor many of the details of the filling replenishing mechanism since these may be of usual construction and are now well understood.

The bracket 4 is secured to the loom frame and has a rearwardly extending portion to which is secured the stud or dead shaft 5. Mounted on the stud or dead shaft 5 is the shuttle feeler 6 having a pin 7 which engages the yielding jaws 8 and 9 of a rocking block 10 mounted upon a rearwardly extending arm 11 secured to the transverse or rock shaft 2. The block 10 is under the influence of a spring 12 which normally holds the jaw 9 in closed relation with the jaw 8 on the arm 11 to enclose the pin 7 between the relatively movable jaws, the construction being such that should the 15 rock shaft 2 be rocked as indicated by the arrow, Fig. 2, the shuttle feeler 6 will be moved rearwardly into shuttle feeler detecting position, as indicated in Fig. 1. Projecting upwardly from the bracket 4 is 20 a guide 13 in the guiding slot 14 on which the feeler moves, and such guide may be either of the inclined type to cause the shuttle 6 to be moved laterally or from the cloth selvage as it partakes of its feeling function and to be moved laterally towards 25 the cloth selvage as it returns to initial position, or it may be straight, either type of shuttle feeler being of a well-known construction.

30 The shuttle feeler 6 has extending therefrom the arm 15 to which is connected the slotted member 16 into the slot of which extends a pin 17 projecting from a lug 18 depending from the usual filling replenishing dog 19. The dog 19 is pivotally connected to the lower extension 20 of the transerrer, and on call for replenishment of filling through the rocking movement of the rock shaft 2 the dog 19 is moved into 35 operative position to be engaged by the usual bunter on the lay as the latter moves frontwardly. The mechanism so far described is or may be of usual construction.

40 The shuttle feeler 6 is provided with a cutter or thread parter to cut or part the filling adjacent the shuttle on call for replenishment of filling. In the present instance the cutter comprises a fixed member 45 21 and a relatively movable cutter member 22 having a tail piece 23 provided with a laterally projecting pin 24 for opening the cutter as the shuttle feeler moves into its rearward shuttle-feeling position.

45 Fixedly mounted on the bracket 4 is the upwardly extending arm 25 on which is mounted the rocking member 26 having a downwardly extending lug 27. The rocking member 26 is under the control of a spring 28 which permits the lug 27 to move frontwardly when engaged by the pin 24 as the shuttle feeler moves frontwardly, but is held from rocking movement in the opposite direction by a stop 29, the construction being such that when the feeler 6 moves to its rearward shuttle-feeling position on call for replenishment

70 ment of filling the projection 27 acting through the pin 24 will open the feeler thread cutter, and after the feeler thread cutter has received the end of the filling a 75 between its cutting members, the frontward movement of the lay acting through the bunter operates the movable thread cutting member to cut the thread, whereupon as the shuttle feeler returns to its frontward initial position, the lug 27 will yield and permit the feeler thread cutter to remain closed. These parts may be of usual construction, and indeed any form of feeler thread cutter or parter may be employed to cut or part the thread adjacent the shuttle on call for 80 replenishment of filling.

85 Mounted upon the breast beam of the loom is the temple arm 31 carrying the usual temple 32 which is provided with a temple thread cutter 33 of usual construction and preferably located adjacent the cloth selvage.

90 The hub portion 34 of the shuttle feeler 6 is provided with a laterally extending sleeve 35 to which is secured by the bolts 36 the upwardly extending support 37 for the thread end holder. The support 37 is preferably made adjustable by forming it in two parts, as shown, and connecting such parts by a bolt 38 which passes through a 95 slot 39 formed in one member, and engages the other member of the arm. By making the supporting arm of the thread end holder adjustable the proper position of the thread end holder may be effected.

100 Extending rearwardly from the thread end holder support 37 is the lower jaw 40 of the thread end holder, which may be formed integral with the arm 37 or secured thereto. Pivotaly mounted on the support 37 at 41 is the upper jaw 42 having a frontwardly extending cam portion 43 and connected to the frontwardly extending cam portion 43 is a pin 44, the upper end portion of which may be turned laterally at 45 to engage an opening in the frontwardly extending cam portion 43. The pin 44 extends downwardly and passes through the guide opening in the lug 46 between which and the cam portion 43 is a spring 47 which normally acts to close the jaws.

110 Secured to the front portion of the loom is a jaw opener 48 having a rearwardly extending end 49 which overlies the frontwardly extending cam portion 43 of the upper jaw. In the present instance, the jaw opener is adjustably secured to the loom frame by a bolt 50 which passes through an opening 51 in the jaw opener, whereby the jaw opener may be adjusted towards and from the front of the loom to locate its rear end in proper co-acting relation with the cam portion 43 of the upper jaw.

120 During normal weaving operations between periods of filling replenishment, the 130

shuttle feeler and the thread end holder are maintained in their frontward position and the rear end portion 49 of the jaw opener bears upon the top surface of the 5 upper jaw rearwardly of the cam portion 43, the result being that the jaws of the thread end holder which are normally closed by the spring 47 are maintained in their closed position by the jaw opener. When, 10 however, replenishment of filling is called by rocking movement of the rock shaft 2, the shuttle feeler and thread end holder move rearwardly and the end 49 of the jaw opener rides over the cam portion 43 of 15 the upper jaw, with the result that as the thread end holder moves rearwardly to engage the filling end between the cloth selvage and shuttle, the jaws are opened, and as the thread end holder and shuttle 20 feeler return to their initial or front position the jaws close upon the thread which is cut by the feeler thread cutter and is moved frontwardly to position the filling end for the action of the temple thread 25 cutter.

The upper jaw 42 of the thread end holder is provided on its inner face with a series of wires 52 which may be conveniently formed of a strip of card cloth 30 ing 53 secured to the surface of the upper jaw. Likewise, the lower jaw 40 of the thread end holder may be provided with friction material 54 which, in the present instance, is shown as a piece of felt secured 35 to the inner surface of the lower jaw. The wire teeth 52 cooperating with the friction material 54 on the lower jaw, in the present instance, effectively hold and maintain the piece of cut filling which is engaged between the jaws and prevent it from dropping to the loom parts beneath. When an 40 accumulation of cut filling ends have been engaged and held by the thread holding jaws, the loom attendant can readily remove 45 these ends by opening the jaws manually, either by lifting the rear end portion of the upper jaw or by pressing upon the cam portion 43 of the upper jaw which is then in its front position.

50 It will be noted that the thread holding jaws extend rearwardly from the support 37 and when the jaws are opened by rearward movement of the thread end holder, the filling ends previously engaged by the 55 jaws are still retained in the jaws due to the frictional engagement either of the wire teeth or the friction material on the lower jaw, so that all liability of the filling ends dropping to the loom parts beneath is avoided, and at the same time an accumulation 60 of these ends between the jaws presents the ends in the most convenient position for the loom attendant to remove the accumulated ends from the jaws at intervals.

65 The wire teeth on the jaw 42 are pref-

erably turned frontwardly, as shown, the effect being that the ends of filling held between the jaws will be gradually worked frontwardly into convenient position for the weaver to remove the accumulation of 70 filling ends by manually opening the jaws when the filling end holder is in front position.

What is claimed is:

1. An automatic filling replenishing loom 75 in which the filling is replenished before complete exhaustion, having in combination a filling cutter in front of the lay adjacent the cloth selvage, a thread cutter for cutting the spent filling adjacent the shuttle, a 80 thread end holder between the cloth selvage and thread cutter comprising two jaws, means for opening the jaws as they move rearwardly on call for replenishment of filling, and acting upon the jaws to maintain 85 them closed when the thread end holder is in frontward position.

2. In a filling replenishing loom, the combination of two cutters for cutting the spent filling, one adjacent the cloth selvage and the 90 other adjacent the shuttle-box, means for operating the cutters, a thread end holder between the two cutters comprising two normally closed jaws one of which is faced with wire teeth, a jaw opener extending from the 95 front of the loom rearwardly for opening the jaws as they move rearwardly and acting to maintain the jaws closed when in front position.

3. In a filling end controller mechanism, a 100 filling end holder comprising two relatively movable jaws one of which is provided with wire teeth to engage and hold a cut filling end, a jaw opener to open the jaws to receive the filling end and acting upon the jaws 105 when closed to maintain them closed to hold the filling end between the jaws.

4. In a filling end controller mechanism, a filling end holder comprising two relatively movable jaws one of which is provided with wire teeth and the other with friction material to engage and hold a cut filling end, a spring for closing the jaws, a jaw opener for opening the jaws and acting to hold the 110 jaws closed after they have been closed.

5. A filling end holder mounted between the cloth selvage and adjacent the shuttle-box comprising two relatively movable jaws one of which has yielding wire teeth and the other a friction material cooperating with 115 the wire teeth of the other jaw to hold a cut filling end between the jaws, and means to open and close the jaws.

6. In a filling replenishing loom, a temple 120 thread cutter, a feeler thread cutter, a filling end holder mounted between the two and comprising relatively movable jaws, one of which is provided with card clothing to frictionally hold the filling end between the 125 jaws, means to move the jaws rearwardly on 130

- call for replenishment of filling, and a jaw 35
opener acting on the jaws to open them as the
jaws move rearwardly, and a spring for clos-
ing the jaws as they move frontwardly.
7. In a filling replenishing loom, the com-
bination of a thread cutter adjacent the cloth
selvage, a thread cutter adjacent the shuttle-
box, a thread end holder mounted between
the two and comprising two jaws, one of
which is provided with card clothing to fric-
tionally hold the filling end between the two
jaws, a jaw opener which acts to open the
jaws as they are moved rearwardly, and a
spring for closing the jaws as they move
frontwardly. 40
8. A filling end holder mounted between
the cloth selvage and adjacent shuttle-box,
comprising a pivotally mounted arm, two
jaws extending rearwardly from said arm,
one having wire teeth to engage and hold a
cut filling end between the jaws, a spring car-
ried by the arm and acting normally to close
the jaws, and a jaw opener acting to open
the jaws for the free reception of the filling
end as they move rearwardly and permit the
spring to close the jaws as they move front-
wardly. 45
9. In a filling replenishing loom, a cutter
adjacent the cloth selvage, a cutter adjacent
the entrance to the shuttle-box, means for
operating the cutters, a filling end holder
mounted between the cutters comprising a
pair of jaws, one of which is provided with
yielding wire teeth, and jaw opening and
closing devices constructed and arranged for
opening and closing the jaws independent
of the cutters to grasp the filling between the
cutters and remove the cut end. 50
10. In a filling replenishing loom, a cutter
adjacent the cloth selvage, a cutter adjacent
the shuttle-box, means for operating the cutters,
an independently mounted filling end holder
between the cutters comprising a pair
of jaws one of which is provided with yield-
ing wire teeth and the other with a fabric
friction pad, and means for opening and
closing the jaws independent of the cutters
to grasp the filling between the cutters and
remove the cut end. 55
11. In a filling replenishing loom, the com-
bination of a temple thread cutter, a thread
cutter adjacent the entrance to the shuttle-
box, means for moving the latter towards
and from cutting position, a thread end
holder comprising two jaws mounted be-
tween the cloth selvage and entrance to the
shuttle box independent of the cutters, means
for moving it towards and from the front
of the loom in a path at right angles to the
lay, a jaw opening and closing means inde-
pendent of the cutters for opening the jaws
to receive the filling thread between them
as the holder is moved towards the rear of
the loom and for closing them when moved
to front position. 60
- In testimony whereof, I have signed my
name to this specification.
- JAMES J. JENNINGS.
